UNITED STATES PATENT OFFICE.

JAMES INGELLS, OF MUSKEGON, MICHIGAN.

DIRECTION-INDICATOR.

1,253,040.

Specification of Letters Patent. Patented Jan. 8, 1918.

Application filed October 5, 1916. Serial No. 123,984.

To all whom it may concern:

Be it known that I, JAMES INGELLS, a citizen of the United States, residing at Muskegon, in the county of Muskegon and State of Michigan, have invented certain new and useful Improvements in Direction-Indicators, of which the following is a specification.

This invention relates to improvements in appliances for indicating in which direction an automobile is about to proceed, to turn, or if it is to stop, or is standing still, and its objects are: first, to indicate to anyone either ahead of, or behind the automobile whether the automobile is to proceed directly ahead, to turn to the right, to the left, or to stop, and, second, to provide an inexpensive and thoroughly reliable implement for the purposes stated.

I attain these objects by the mechanism illustrated in the accompanying drawing, in which Figure 1 is an end elevation, and Fig. 2 is a front elevation of the implement; Fig. 3 is a front elevation of one end of the inclosing case showing how the ring that supports the inner, or indicator case is connected therewith; Fig. 4 is a longitudinal section of the indicator on the line 4—4 of Fig. 2, and the wire protecting case on the line 1—1 of Fig. 1; Fig. 5 is a plan of the blank from which the end of the case is formed; Fig. 6 is a side view of the same showing the opening for the passage of the actuating cord or strap; Fig. 7 is a transverse section of the supporting hub of the inner case; Fig. 8 is a like view of the reflector; Fig. 9 is a transverse section of the bulb supporting flange with the supporting tube in place.

Similar reference characters refer to similar parts throughout the several views.

In the construction of this implement I provide an inclosing case consisting of the side walls 1 made of very thin sheet metal having a series of slots, *k*, therethrough for the passage of the lugs *a* on the offsets *a'* on the ends 2', 2 of the case. The ends of the case are practically the form shown in Fig. 1. The length shown in Fig. 5, from the edge of the end piece 2 to the dotted lines across near the ends of the lugs *a* is designed to form offset bearings *a'* for the ends of the casing sides 1, between the lugs proper and the outer surfaces of the ends, as indicated in Figs. 2, 3 and 4. I prefer that the corners, *p*, of the ends 2 be so

formed that they may be bent on the lines *n*, see Fig. 5; to form bearings through which the screws *e*, *e* may be passed and secured for securing the casing and front 60 firmly in place upon the ends 2, 2, and when forming these lugs I aim to set their outer surfaces back from the edges of the ends the thickness of the metal from which the casing is made, as indicated at *m*, *m* in 65 Fig. 1, and by the dotted lines *n*, *n* in Fig. 5. *m'*, *m'*, in Fig. 2 represent the edges of the casing as indicated at *m*, *m* in Fig. 1. 6 represents the glass front of the outside casing, and this is secured to the casing by 70 means of the frame 24, the flanges *o* of which are lapped over the surface of the casing 1, as shown at *o*, *o* in Fig. 1, and indicated at *o'* in Fig. 4, and is secured thereto by means of the same screws, *e*, *e* that secure the edges 75 of the casing to the ends 2.

The ends 2 have each an offset 2' that forms a chamber or bearing for the reception and free revoluble action of the inner case supports 8, 8 that are formed with 80 flanges 8', see Fig. 7, designed to bear upon the supporting rings 16, as indicated in Figs. 3 and 4, the rings 16 having central holes of a proper size so the bearings 8, 8 may pass freely through them and revolve 85 freely therein. One of the bearings 8 is arranged to have a cord or strap 20 connected therewith and passed through the opening 19 in the offset 2', at one end of the case, and thence to any convenient position so the 90 operator may manipulate the indicator case inside of the inclosing case 1—2.

The indicator case is made up of the bearings 8, one at each end, metal corners 22, secured at the ends to the flanges 8' of 95 the bearings 8, and glass panels 21, one on each of the four sides of the case ends or bearings, to form a case for the storage of the electric bulbs 12, and for carrying the indicator symbols 7 and 7'. These symbols are 100 formed in, or through very thin metal, or other suitable material, as indicated at 23, and may be in the form of arrows, as indicated in Fig. 1, in which case there must be an arrow on each of two sides of the case: one 105 pointing to the right, as in Fig. 1, and the other pointing to the left so as to readily designate which way the automobile is to be turned. Opposite the arrows may be other indicator symbols, as the word "Go", as indicated in inverted position in the sectional view of the case in Fig. 4, at 7', or, if it is

desired to stop the automobile following, the word "Stop" or other suitable word, or, even, a red light may be displayed. It is, also, desirable to have the glass 21, that 5 covers each symbol, of different colors as, for instance, a red glass for one symbol, a blue glass for another, a green glass and a yellow glass for others, &c. In Fig. 4 I have indicated the symbol as behind a green 10 glass.

In the use of indicators of this class it has always been found difficult to properly distribute the light inside, or back of the symbol case. I obviate this difficulty by placing 15 a small concave reflector, as 14, in each end of the case within the bearing *g*, and properly place electric light bulbs 12 to equally diffuse light throughout the entire inside of the indicator case, and each and 20 every part of the symbol will be as clear and distinct as each and every other part thereof. I provide for carrying the indicator case back into normal position after it has been operated by the use of the strap 20, by connecting a spring 25, at one end to the bearing 8, as at *j*, and the other end to the offset 2' of the case end, as at *i*, so the recoil of the spring 25 will always return the indicator case into normal position as soon as the 30 strap or cord 20 is released.

My manner of supporting the electric bulbs in this indicator consists in placing a suitable hub, as 9, upon each end of the case, and securing it there by any available 35 means, as by the screw *f*, and screws or rivets *h*, *h*. I then screw, or otherwise secure a suitable tubular bearing, as 10, into, or through each hub. The necks of the bulbs 12 are inserted into the inner ends of these 40 tubes and a nonconducting substance 11 is inserted into the outer end of each of the tubes, as indicated in Fig. 4, so that the bulbs are held rigidly in place while the indicator case and the reflectors are revolving 45 around them.

The electric current for illuminating the indicator after dark is conducted over the conductor wires stored in the casing 18, over the posts 17 and the wires 13 to the bulbs 50 12, and returned through the metal case by proper connections, as at *c*, *c*.

I provide for storing and protecting the electric conductor wires 13, 13 by means of a casing 3 that covers the tubular connection 10, and is provided with an arm 4 that passes back into position to be secured to the end flanges 2', as indicated at *g*, *g* in Fig. 1, and the casing 3 may be secured to the hub 9 by any available means as, for instance, 60 the screw *f*.

I have provided for securing the ring 16 to the end flange 2', at each end of the case, by forming lugs *b* on the flange 2' and bending them inward over the edge of the rings, as 65 indicated in Figs. 3 and 6.

15 indicates an air chamber between the indicator case and the inclosing case, designed to protect the indicator case from sudden exposure to extreme cold, and thus protecting the glass over the symbols, but 70 inside of the inclosing case, and *d* represents a hole through the bearing 8, the reflector 14 and the hub 9 for the passage of the tube 10.

This indicator may be secured to the vehicle by any of the well known devices for 75 securing this class of indicators to vehicles, and at any place on the vehicle that may be desired, and it may be used at the front end, or at the hind end, or both ends of the vehicle, as desired; and the connections between the indicator and the chauffeur may be of any of the well known devices or connections now in use for the purpose, or for similar purposes, as the indicator is not designed exclusively for use upon automobiles, 80 but may be used in various places where such devices may be made available.

What I claim as new and desire to secure by Letters Patent of the United States, is:

1. In a direction indicator for automobiles, an outer case, a revoluble indicator case mounted therein, and having direction indicating symbols mounted thereon, a ring mounted in each end of the stationary case, a bearing formed on each end of the revoluble case and fitted to revolve freely in the rings, an electric light bulb mounted in each end of the stationary case and extending into the revoluble case, reflectors properly mounted in the revoluble case to illuminate the symbols, electric connections with the bulbs, and means for revolving the inner case to expose the desired symbols. 95

2. In a direction indicator, a stationary case, a revoluble case mounted inside the stationary case and having indicator symbols thereon, a transparent front in the stationary case to disclose the said symbols, rings mounted in the ends of the stationary case for revolubly supporting the revoluble case, a strap 100 connected with one end of the revoluble case, a spring connected with the other end of the revoluble case and with the stationary case, means for properly actuating the revoluble case through the medium of the strap and spring, a concave reflector mounted in each end of the revoluble case, and facing to the center of the said case, an electric light bulb mounted in each end of the stationary case wholly within the revoluble case, and proper 110 electric connection with said electric light bulbs. 115

3. In a direction indicator, an outer case constructed with ends, lugs extending inward and having their ends turned outward 120 at right angles, a casing extending partly around the ends and having slots at its ends to receive the outwardly turned ends of the lugs, and also having a transparent opening to disclose indicator symbols, 130

- clamping lugs on the ends, chambers formed in the ends of the case, a ring mounted in each end of this case and secured therein by bending the clamping lugs over its edges, 5 a revoluble inner case having outwardly pressed end bearings arranged to be passed through the rings in the outer case and revolve freely therein, electric light bulbs mounted at the ends of the outer case, and 10 concave reflectors mounted in the ends of the inner case back of, and concentric with the light bulbs.
4. In a direction indicator, an outer case having a chamber offset in each end, a hub and a tubular bearing connected with each 15 end of the outer case, electric light bulbs mounted in said tubular bearings, proper electric connections with said bulbs, a guard connected with each end of the outer case 20 for protecting the electrical wire connections, a supporting ring mounted in each end of the stationary case, an indicator case revolvably mounted in the supporting rings
- within the stationary chamber; in combination with concave reflectors mounted in the ends of the indicator case around the electric light bulbs. 25
5. In a direction indicator, ends having lugs turned inward at right angles to form bearings, then outward to form retaining 30 lugs, a metal casing having slots in the ends to receive the retaining lugs and form a stationary chamber having a transparent opening, tubular bearings formed in the ends of the stationary chamber, electric light bulbs 35 securely mounted in said bearings, proper electric connections with the bulbs, a revoluble case mounted in the stationary chamber, means for properly actuating said revoluble case, reflectors so mounted in the revoluble case as to produce an equal distribution of light through the indicator symbols. 40

Signed at Muskegon, Michigan, September 29, 1916.

JAMES INGELLS.
